UNITED STATES PATENT OFFICE.

JOHN C. MARTIN AND NORRIS C. BUCKMAN, OF SPOKANE, WASHINGTON.

LIQUID-DISPENSING APPARATUS.

1,188,468.

Specification of Letters Patent. Patented June 27, 1916.

Application filed February 15, 1915. Serial No. 8,288.

To all whom it may concern:

Be it known that we, JOHN C. MARTIN and NORRIS C. BUCKMAN, citizens of the United States, residing at Spokane, in the county of

5 Spokane and State of Washington, have invented certain new and useful Improvements in Liquid-Dispensing Apparatus, of which the following is a specification.

This invention relates to improvements in dispensing apparatus for dispensing a predetermined amount of a commodity upon the insertion in the apparatus of a coin or token of a predetermined denomination or value.

15 The invention relates more particularly to an apparatus of this character which is particularly adapted to dispense liquid and has to do more particularly with an apparatus for dispensing gasoline to supply automobiles, although the invention is not in any way limited to this particular utility.

One of the objects of this invention is to provide a supply tank into which the quantity of liquid to be dispensed is supplied, the tank being provided with improved means for automatically shutting off such supply when the latter has reached a predetermined volume.

Other features and objects of the invention will be more fully described in connection with the accompanying drawings and will be more particularly pointed out in and by the appended claim.

In the drawings:—Figure 1 is a view in side elevation illustrative of one form of our invention. Fig. 2 is a view looking toward the right of Fig. 1. Fig. 3 is a vertical sectional view of the upper portion of the apparatus shown in Fig. 1. Fig. 4 is an enlarged sectional view of valve and coin controlled mechanism similar to that shown in Fig. 3, with the parts in a different position. Fig. 5 is a sectional view similar to Fig. 3, showing the upper portion of the latter, with a float in a different position. Fig. 6 is a sectional view on line 6—6 of Fig. 3. Fig. 7 is a detail plan view of an improved coin retainer.

Like characters of reference designate similar parts throughout the different figures of the drawings.

As illustrated, our invention includes an upright supporting standard 1 in which is incorporated any suitable form of pump adapted to be operated by a manual member such as a crank 2. A supply pipe 3

leads from the pump, it being understood that the latter will be connected with the source of supply of gasoline or other liquid to be vended.

50 Mounted upon pump standard 1 by means of brackets 4, is a tank structure which comprises a tank 5 and a housing 6. Within the housing 6 is a valve casing 7 which is connected with supply pipe 3 and also 65 with a dispensing pipe 8. Dispensing pipe 8 is equipped with a flexible hose connection 9 terminating in any suitable form of valve 10. Valve 10 is adapted to be partly inserted in the gasoline tank filling opening of an automobile. In alignment with supply pipe 3 is an extension 11 which opens into tank 5. Also, dispensing pipe 8 is in alignment with an extension 12 which opens into tank 5. Within valve casing 7 70 are two valve closures 13 and 14 which are connected by a rod 15 in such a manner that they will always maintain one of the pipe openings into the tank closed, while the other pipe opening is open, whenever 75 said valves are in either of their extreme positions. As shown in Fig. 3, the valves are in an ingress closing and an egress opening position, whereas in Fig. 4, they are in an ingress opening and an egress closing position.

80 The valve closures are normally held in the position shown in Fig. 3 by an expansively-acting spring 16 which is interposed between closure 13 and cap 17. Rod 15 extends through a suitable packing gland 85 18 and is connected with a portion of the coin controlled mechanism hereinafter referred to. Fixed on the rod 15, preferably between closures 13 and 14, is one member of a trip device which may be in the form 90 of a sleeve 19 having a cammed upper portion 20. Projecting through the valve casing 7 is the other member of the trip device which is in the form of a stem 21. Stem 21 is pivoted at 22 to a lever 23, the latter 95 being pivoted at 24 to a part of the valve casing 7. A connecting rod 25 is pivoted to lever 23 and extends upwardly through a centrally disposed pipe 26 projecting upwardly from the bottom wall of tank 5. A 100 tubular member 27 is slidably mounted on guide 26 and extends above the latter and on the upper end of the same a collar 28 is 105 adjustably mounted on the connecting rod 25, by means of a set screw 29. The function of collar 28 is not only to limit downward movement of rod 25, beyond a pre-

determined extent, but also to form an abutment for the upper end of guide 27 when the latter is elevated so as to lift the stem 21 out of engagement with sleeve 19, as will 5 presently appear. When hub 19 is released from the set position shown in Fig. 4, the spring 16 will be free to act on the valve closures 13 and 14 to shift the latter into the position shown in Fig. 3.

10 Within tank 5 is a float 30 which is centrally bored to extend about guide 27 and which is elevated in the tank 5 by influx of the supplied liquid. In order to transmit motion from the float to the connecting rod 25, an adjustable abutment 31 is secured upon guide 27 by a set screw 32.

15 The tank 5 is provided with a cover 33, hinged at 34 to swing about an axis at right angles to the axis of the tank. A lug 35 projects from the cover and is apertured to receive a fastening means in the form of a rod 36, having a head 37. The lower end of rod 36 extends through apertured lugs 38, projecting from the housing 6. The 20 housing 6 is provided with a door 39 which is hinged at 40 to swing about an axis parallel with respect to the axis of the tank and at right angles to the axis of hinge 34. Upon the door 39 is an apertured lug 41 25 through which the rod 36 is adapted to extend to lock both the cover and the door in a closed position. The rod 36 may terminate in an eye 42 which may be provided with any form of locking device.

20 In the housing 6 is a coin chute 43, suitably mounted in a bracket 44. Beneath the coin chute 43 is a slidably mounted coin receiver 45 having a coin slot 46, for receiving a coin from chute 43. The receiver 45 reciprocates on guides 47 which also function to hold a coin of a predetermined denomination from falling out of the receiver 45. However, it will be seen by reference to Fig. 6 that if the inserted coin were of a 25 too low denomination, it would fall through the receiver. An abutment 48 serves to limit movement of receiver 45 to the right of Fig. 3 to bring the slot 49 into registry with chute 43. Receiver 45 is fixedly connected with valve rod 15 as indicated by the screw threads 50. The receiver 45 is provided with a bore 51 which intersects slot 49 so as to permit passage therethrough of a plunger 52 when a coin is not present 30 in slot 49. When a coin is lodged in slot 49 then the plunger 52 will abut against the coin and force the receiver 45 from the position shown in Fig. 3 to the position shown in Fig. 4. This last position is the 35 one which the valves occupy when liquid is free to be supplied to tank 5.

Plunger 52 is slidable through the end wall of housing 6 and also through abutment 48 and we provide a spring 53 for normally 40 forcing the plunger 52 into the retracted

position shown in Fig. 3. A collar 54 forms an abutment between the spring and the plunger 52. A coin box 55 opens into the housing 6 at 56.

In order to support coins of the proper 70 size in the receiver 45, we incorporate the guides 47 in a slide 57. Slide 57 has flanges 58 in which elongated slots 59 are formed. This guide structure, which is also a coin 75 retainer, is slidably mounted on the bottom 75 wall of housing 6 by means such as rivets 60. An opening 61 serves to receive a projection 62 on collar 54, as will be seen more particularly by reference to Fig. 4.

Now assuming the parts to be in the position shown in Fig. 3, a coin will first be inserted and then the plunger 52 will be forced against the coin to move the parts into the position shown in Fig. 4. This will open ingress to the tank and close egress therefrom. The pump will now be operated to force a supply of liquid into the tank 5 which will elevate float 30 until it coacts against abutment 31 whereupon the trip device will be actuated to release valve rod 15. 80 Spring 16 will instantly act to throw the valve closures 13 and 14 into the position shown in Fig. 3 so as to close ingress into the tank and open egress therefrom. The valve 10 may be held closed until the proper 85 filling connection is made with the tank to be filled. Thus it will be seen that by means of our improved invention, the supply is automatically shut off while the pump is in operation when a predetermined amount of 100 liquid has been received in the tank 5, and further, that the tank 5 will simultaneously be opened for delivery of such quantity.

Now in order to prevent discharge of the coin from the receiver 45 in the event that 105 the plunger 53 has not been forced to a final position to the left of Fig. 4, it will be seen that the retaining guides 47 prevent the coin from falling into box 55 when the parts are in the position shown in Fig. 4. However, when the plunger is released for retraction by spring 53, the projection 62 will force the retainer 57 sufficiently to the right of Fig. 4 to permit the coin to drop.

If desired, a rod 63 may be provided with 110 a spring 64, abutting against a lug 65 in order to more quickly retract retainer 57 to the right of Fig. 4. However, we do not consider this feature absolutely essential in all embodiments of the invention.

While we have herein shown and described one specific form of our invention, we do not wish to be limited thereto except for such limitations as the claim may import.

We claim:

In a liquid dispensing apparatus, a tank having ingress and egress openings, spring controlled valve mechanism for maintaining one of said openings closed and the other 100

open, a fixed vertically disposed circular guide in said tank, trip mechanism for said valves including a trip rod extending upwardly through and above said guide, a sleeve freely movable longitudinally on said guide, and extending above the latter, a stop on said rod engaging the top of said sleeve to prevent independent upward movement of the latter with respect to the former, an abutment on said sleeve, and a float freely movable upwardly on said sleeve under action of incoming liquid into engagement with said abutment to raise said sleeve and rod to trip said mechanism and actuate said valve to close ingress and open egress to 15 and from said tank, substantially as described.

10 In testimony whereof we affix our signatures in presence of two witnesses.

JOHN C. MARTIN.

NORRIS C. BUCKMAN.
